METAL SPOOL

Stephen George, Fairfield, Conn., assignor to The Bridgeport Tool and Die Company, Incorporated, Bridgeport, Conn., a corporation of Connecticut

Application February 10, 1949, Serial No. 75,539

3 Claims. (Cl. 242—70)

1
This invention relates to a metal spool, such, for example, as used for photographic or camera film and the like, and has for an object to provide an improved construction of spool in which the core is bent up from a piece of sheet metal and is provided with improved means for interlocking the abutting edges of this piece of metal to greatly increase the resistance to torsional strain on the spool, and the edges are locked against relative longitudinal movement in either direction.

Another object is to provide a construction in which the abutting joint at the opposite ends of the longitudinal slot provided for inserting the end of the protective paper for the film is located out of alignment with the slot, so that should the joint open up slightly the edge of this paper will not be caught in this joint, and thus be likely to be torn, causing light leakage and ruining of the film.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a side elevation of the spool showing the abutting joint between the edges of the rolled-up piece of sheet metal forming the core;

Fig. 2 is a similar view looking toward the opposite side;

Fig. 3 is an end view looking from the right of Fig. 1;

Fig. 4 is a transverse section substantially on the line 4—4 of Fig. 2;

Fig. 5 is an enlarged perspective view of the core with the flanges removed;

Fig. 6 is a transverse section thereof;

Fig. 7 is a detail elevation on an enlarged scale showing the edges of the abutting joint separated, and

Fig. 8 is a transverse section showing somewhat diagrammatically the dies and operation of the final bending action in closing together the edges of the core.

The spool comprises the cylindrical barrel or core portion 10 and the sheet metal flanges 11 and 12 secured to the opposite ends of the core by any suitable means, such, for example, as spot welding as shown at 13, one of these flanges being provided with a circular opening 14 forming a pivot and the other end provided with an elongated slot 15 for the key operating means. The

2
core 10 comprises a piece of sheet metal bent up into cylindrical form which thus provides a tubular core to the opposite end edges of which the flanges are secured. The opposite edges of this core member comprise interlocked abutting portions at the opposite ends of the core and an intermediate portion between these abutting end portions, the edges of the intermediate portion being laterally spaced, as shown at 16 and 17, to provide a longitudinal slot 18 through which the end of the protective paper strip of the photographic film is threaded. A similar slot 19 is provided on the opposite side of the core, but is of shorter length than the slot 18, as usually the free end of the paper strip is tapered. To prevent tearing or injury to the paper the opposite edges of this slot 19 are rounded and rolled backwardly as indicated at 20.

The opposite abutting end portions of the free edges of the sheet metal member each comprise an inner lug or tongue 21 and an outer lug or tongue 22 projecting laterally from the respective free edges of the sheet metal member, and the two lugs lie side by side, as indicated at 23. Each edge is provided with a recess in which the free end of the lug from the opposite edge is seated. Thus the free end of the lug 21 is seated in a recess 24 extending backwardly from the opposite edge 17 of the slot 18 and the lug and recess are located at the end of this slot, the recess being the same width as the lug 21. With this arrangement the inner side edge of the lug 21 forms the end of the slot 18 and the lug 21 is held against longitudinal movement in either direction by the edge or shoulder 25 of the other lug 22 and the edge or abutment shoulder 26 of the opposite side of the recess, thus greatly increasing the resistance to torsional strain and enabling the spool to resist much greater stresses without opening the joint or permitting the spool to be forced out of shape. Another advantage of this construction is that the abutting joint 27 formed at the free end of the lug 21 and the bottom of the recess 24 is set back from and thus is out of alignment with the edge 17 of the longitudinal slot 18. Thus should the forming dies become worn so that the end of the lug and the bottom of the recess are not properly seated, or if the joint should be slightly opened, there is no chance of the edge of the protective paper strip entering or being caught in this joint, as would be the case if it were in alignment with the edge 17 of the slot. This prevents the paper being caught and torn, which might permit light leakage and ruining of the film.

The lug 22 extends from the opposite edge to

the lug 21 and seats in a recess 28 in the edge on which lug 21 is located. The bottom of this recess is set back from the opposite edge 16 of the slot as indicated at 29 Fig. 7, and this distance is preferably the same as the distance the bottom edge 24a of the recess 24 is set back from the edge 17 of the slot 18, as shown at 30 in Fig. 7. In other words, the length of the lug 21 beyond the center line 31 of the slot 18, as shown in Fig. 5 and indicated by the distance 32, is the same as the length of the lug 22 on the opposite side of the centerline 31 as indicated by the distance 33. This is important in making the last bending or forming operation to complete the circular shape of the core in the forming dies as shown in Fig. 8 (in which the partially formed blank is shown at 35 and the upper and lower dies at 36 and 37 respectively), because it makes the amount of metal on opposite sides of the center line 34, corresponding to the center line 31, equal, so that the forces of the die in the bending operation are equal on opposite sides of this center line and there is therefore no tendency to force one side off the center. This greatly facilitates the operation of getting the edges to come properly together. Where they are not even, difficulty is experienced in this respect. Also, as pointed out above, it secures a double locking effect of the abutting edges at each edge of the core against torsion and twist or relative sliding movement of the edges in either direction, so that the spool is much stronger at its opposite ends. If it is locked in one direction only as in some forms, and there is some inaccuracy in the dies at one end, then there may be a locking only at the other end of the spool. In the present construction should it not be properly locked at one end there is still a double lock at the other end, giving double safety and much less liability of the joint opening up. In other words, as it is locked and supported in both directions at both ends of the core, even if the lock is lost at one end there is a locking effect in both directions at the other end.

Having thus set forth the nature of my invention, I claim:

1. A metal spool for camera film and the like comprising a central barrel portion and end flanges secured to the ends of the barrel portion, said barrel portion being provided with a longitudinal slot terminating at its opposite ends spaced from the ends of this portion, the end portions beyond the slot including a longitudinal joint comprising abutting edges, one edge adjacent the end of the slot being recessed backwardly from the edge of this slot, a lug projecting

from the other edge and seated at its free end in the recess, said latter edge being provided with a recess on the outer side of the lug extending backwardly from the second edge of the slot, and a lug on the first edge located at the outer side of the first lug in the latter recess and projecting at its free end with this recess beyond the second edge of the slot an amount substantially equal to the depth of the first recess.

2. A metal spool for camera film and the like comprising a tubular sheet metal core, and flanges attached to the ends of the core, said core comprising a sheet metal member bent into tubular form and having interlocked edges, said edges having at each end of the core outer and inner lugs side by side extending in opposite directions and each edge being provided with a recess opposite to and receiving the end of each lug on the other edge, the edges between the inner lugs being spaced to form a longitudinal slot in the core, and the bottom edge of each recess for both the inner and outer lugs being set back from the edge of the slot on that side of the slot whereby the inner lugs are each held by abutments on opposite sides of this lug against longitudinal movement in either direction.

3. A spool for camera film and the like comprising a metal core and flanges attached to the core, said core comprising a sheet metal member bent to tubular form and having opposed edges abutting at the opposite end portions of the core and spaced apart between said abutting end portions to provide a longitudinal slot, the edges of said abutting end portions including an inner and an outer lug projecting forwardly from the respective edges of the slot and lying side by side, and each edge including a recess opposite to and in which the free end of each lug on the opposite edge portion is seated and with the inner edge of each recess spaced backwardly substantially the same amount from the edge of the slot on the side on which the recess is located.

STEPHEN GEORGE.
